ANCHOR LOCK FOR METAL ROOFING

Arlington Selph, Guilford, Ind., assignor of one-fourth to Edythe B. Levi, Cleveland, Ohio

Application July 1, 1935, Serial No. 29,328

1 Claim. (Cl. 108—33)

This invention relates to anchor locks for metallic roofs and is especially adapted for the securing of metallic sheeting in overlapped relation to form a leakproof seam and has for the primary object the provision of a device of this character which will efficiently join together the overlapped sheeting without the use of nails and like fasteners and which will permit the metallic sheeting to readily expand and contract due to varying temperatures without the danger of injury thereto or the development of leaks, which frequently occur when nails and like fasteners are employed.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a fragmentary sectional view showing metallic sheeting arranged in overlapped relation to form a seam between the sheeting and secured together by my invention.

Figure 2 is a fragmentary sectional view showing the fastening means prior to the connection of the metallic sheeting thereby.

Figure 3 is a view similar to Figure 2, showing the fastening of the metallic sheeting by my invention.

Figure 4 is a fragmentary plan view showing the formation of tongues and openings in the metallic sheeting.

Figure 5 is a fragmentary sectional view illustrating a modified form of my invention, prior to the joining of the metallic sheeting.

Figure 6 is a view similar to Figure 5 showing the sheeting joined together by my modified form of invention.

Figure 7 is a fragmentary plan view showing the form of opening to receive the form of anchor disclosed in Figures 5 and 6.

Referring in detail to the drawing, the numeral 1 indicates roof sheathing on which is mounted metallic roof sheeting 2 of corrugated formation and arranged to overlap one another and thereby effect a seam between the sheeting. The sheeting which is arranged innermost at the seam is designated by the character A, and is provided with an attaching flange 4 having elongated openings 5 to receive nails or like fasteners 6 which are driven into the sheathing 1. The sheeting which is disposed outermost at the seam is designated by the character B and has suitably secured to its inner face lugs 7, each formed with a head 8 provided with oppositely extending

beveled faces 9 and 10. The sheeting A has formed therein openings 11 and the sheeting A adjacent said openings is slotted to define tongues 12 with the openings 11 located therein. When the sheetings A and B are brought together in overlapped relation the lugs 7 pass through the sheeting A by upsetting the tongues so that said tongues frictionally engage the beveled faces 9 of the lugs and thereby effectively secure the sheetings A and B together capable of a limited movement to compensate for expansion and contraction due to varying temperatures.

When desiring to secure together metallic sheeting of the non-corrugated type, lugs 13 are employed each including a tapered head 14. It is preferable that the head 14 be bifurcated so that it may contract when passed through an opening 15 of a keyhole slot formation. After the passing of the head 14 through the opening 15 the shank of the lug is then moved into the restricted portion of the opening, thereby effectively locking the sheeting together. Thus it will be seen that when sheeting is assembled and secured together by my invention, the outer sheeting of the seam is non-punctured by fasteners or like devices and thereby will materially eliminate the possibility of leaks.

Having described the invention, I claim:

In combination with roof sheetings adapted to be arranged in overlapped relation to form a seam, tongues struck out from one of the sheetings and arranged in cooperating pairs, the tongues of each pair having substantially semi-circular cut away portions at their free edges, whereby a circular opening is defined by each pair of tongues, and anchoring lugs secured to the other sheeting, each lug having a head larger than said circular opening and comprising a pair of truncated superimposed cones disposed with their bases in opposed abutting relation, said abutting bases providing a relatively small intermediate band of uniform diameter, said cones gradually tapering in directions opposite to one another, the lower of said cones adapted to act as a wedge to spread the tongues of a pair when the head is being threaded through the opening and the upper of said cones adapted to be engaged throughout its entire periphery by the free semi-circular edges of a pair of tongues when the head has been threaded through the opening, said tongues in their operative position being disposed at a substantially 45° angle to the line of movement of the lug when being inserted and removed from said opening.
